BOTTLE SEAL

Ward Ashton, Ottawa, Ontario, Canada

Application June 24, 1932, Serial No. 619,104
In Great Britain January 19, 1932

2 Claims. (Cl. 215—8)

The invention relates to bottle seals generally, and more particularly to a seal that can be readily inserted and permanently secured in the neck of a bottle, and which must be broken or punctured to permit removal of the contents of the bottle.

An object of the invention is to provide a bottle seal of very simple, but durable construction, that will at comparatively negligible cost more 10 efficiently perform the functions required of it.

Another object is the provision of a seal of this description adaptable to any form of bottle for, in particular alcoholic beverages which will render tampering therewith impossible without 15 being detected.

With the foregoing and other objects herein-
after more fully referred to, the invention com-
prises a sleeve member adapted to fit snugly into
the neck of a bottle, and so formed as to provide,
20 in combination with the bottle-neck, a space for
molten or liquid material. The sleeve member
is also formed with a vertically extending pas-
sageway provided, at the lower end with a dia-
phragm, having a penetrable center registering
25 with said passageway, and which must be broken
before the contents of the bottle can be poured
out.

The invention will be best understood by refer-
ence to the following description, when taken
30 in connection with the accompanying illustration,
of one specific embodiment thereof, while the
scope of the invention will be more particularly
pointed out in the claims.

Reference will now be had to the drawing and
35 the example of the invention disclosed therein,
solely for illustrative purposes.

In the drawing, in which like numerals of
reference, indicate corresponding parts in each
figure:—

40 Fig. 1 is an enlarged sectional view of the
neck of a bottle equipped with the seal.

Fig. 2 is a section on line 2—2 of Fig. 1.

Fig. 3 is a plan view of the seal.

Referring now more particularly to the draw-
45 ing A, designates the seal as a whole and B, the
neck of a bottle fitted with the seal, and in the
present instance threaded on the outside to en-
gage with the usual cap.

The member A, comprises a body 10, of any
50 suitable material, having therethrough a pas-
sage way 11, and in the present example, formed
with a top flange 12, to engage with shoulder
13, on the bottle-neck B, which is also bulged
as at 14, to provide a space 15, between the neck
55 and the member A, for molten or liquid cement-

ing material, whereby the member A becomes
part of the bottle-neck B. A passage 16, is also
provided in the member A, communicating with
the space 15, for injecting the cementing ma-
terial. The lower end of the seal main passage 60
way 11, is closed by a diaphragm 17, having a
penetrable center 19, registering with the said
passage, which when punctured permits the flow
of liquid from the bottle. The sides 18, of the
diaphragm are grooved as at 20, to engage with 65
a washer, 21, of any suitable material and on
which the body 10, presses down. Furthermore
this washer is arranged to fit between the con-
verging portion 22, of the bottle-neck, below
bulged portion 14, and is thus securely held there 70
by compression. The body 10, is, as here shown
grooved at 23, to more effectively engage with the
cementing material.

It will be understood that the member A, may
be formed to provide a space 15, for the filler 75
material, when forming the stopper seal for a
straight shaped bottle-neck. Again the body 10,
may be made in two pieces superimposed, and
permitting the filler to be inserted over one piece
before the other or top piece is placed in posi- 80
tion. Also double seal may be provided by hav-
ing a skin of suitable material across the top of
the member A, closing the passage way 11.

In operation, the bottle having been filled, the
member A, is inserted as a stopper and pressed 85
down on the washer, preferably of cork, 21. The
filler such as liquid cement, molten glass or the
like, is injected into the circumferential space
15, allowed to set and thus permanently securing
said member in position. Nothing can then be 90
taken from the bottle without puncturing the
diaphragm 17, first, thereby plainly indicating
the bottle has been used or tampered with. The
punctured diaphragm is readily visible from
without the bottle by tilting it back slightly. 95

Various forms of the device will suggest them-
selves to those skilled in the art, and it is there-
fore not intended that the present application
should be limited to any particular form of con-
struction, so that modifications may be made in 100
the device, as described, within the scope of the
claims, without departing from the spirit and
scope of the invention.

What I claim for my invention is:—

1. A bottle-seal comprising a stopper member 105
having a main passageway therethrough, a pen-
etrable seal for said passageway, and an auxiliary
passageway in said stopper for the injection of
filler material around the body of the stopper
member to permanently retain the stopper in the 110

neck of the bottle, the interior of the bottle neck and the exterior of the stopper being of such form as to provide a recess therebetween.

2. In combination with a bottle a stopper having a main passage therethrough for the reception and discharge of liquid, a penetrable seal for, at least one end of said passage the interior of the bottle neck and the exterior of the stopper

being of such form as to provide a recess therebetween and means for admitting a liquid filler to said recess, after the stopper has been inserted, to permanently retain the stopper in the neck of the bottle, and a compressible washer surrounding the sealed end of the stopper and contacting with the interior of the bottle neck. 80
